UNITED STATES PATENT OFFICE

2,386,788

SUSPENSION MEANS FOR AUTOMATIC WASHERS

Peter Eduard Geldhof and Luther Ringer, St. Joseph, Mich., assignors to Nineteen Hundred Corporation, St. Joseph, Mich., a corporation of New York

Original application December 2, 1940, Serial No. 368,190, now Patent No. 2,347,190, dated April 25, 1944. Divided and this application May 1, 1943, Serial No. 485,293

1 Claim. (Cl. 243—20)

This invention relates to a novel means for supporting and carrying the washing and operating mechanisms of an automatic washing, rinsing and drying machine. It provides a means for resiliently supporting a complete operating and control mechanism for such a machine within the rigid frame structure therefor.

The instant application is a division of application Serial No. 368,190, entitled "Automatic Washer" filed December 2, 1940, by Peter Eduard Geldhof and Luther Ringer, and which issued on April 25, 1944, as Patent No. 2,347,190.

It is an object of the present invention to provide a yieldable supporting means for a washing, rinsing and drying machine such that the operating mechanism thereof is carried in a substantially floating relationship with respect to the rigid frame structure or housing, whereby the vibration or other operational shocks or jars initiated by the operating mechanism transmitted to the housing will be greatly minimized, if not completely eliminated.

It is a further object of the invention to provide suspensions for the operating and control mechanisms of such machines to permit a certain degree of freedom of lateral movement of the mechanism with respect to the housing structure therefor. The provision of even restricted freedom of lateral movement serves to correct for and minimize the effect upon the apparatus of unbalanced loading of the centrifugal means during its actuation for carrying out the drying operation.

It is an aim of the present invention to provide, in a centrifugal type of device embodying a housing and a container therein in which centrifugal means is disposed, means for supporting said container in the housing comprising a plurality of suspensions extending between the bottom of the container and the wall of the housing. Each of the suspensions includes a supporting element having an end cushioned in dampening means.

In accordance with the general features of this invention, there is provided a supporting frame, a base, and suspension means extending between said frame and said base, each of said suspension means being characterized by a pair of brackets joined by a connecting member so constructed that it provides a resilient, swingable mounting for said base with respect to said frame.

The novel features which we believe characteristic of our invention are set forth with particularity in the appended claim. Our invention itself, however, both as to its manner of construc-

tion and operation, together with further objects and advantages thereof, may best be understood by reference to the following description taken in connection with the accompanying drawings, in which:

Figure 1 is a horizontal section through a washing, rinsing and drying machine looking down on the floating mounting for the tub and drive mechanism which represents one embodiment of the present invention;

Figure 2 is a partial vertical section through one of the supporting means shown in Figure 1 taken along the line II—II; and

Figure 3 is a sectional view of one of the lower suspension pad socket members taken along the line III—III of Figure 2.

As will best be seen from Figure 1 of the drawings, the automatic washing, rinsing and drying machine with which the suspension means of the present invention is advantageously employed includes, in general, a casing 10 which houses the entire mechanism and controls therefor. Secured to two of the inner faces of the casing 10 are bars 11 which are bolted to the casing as by means of bolts 12. These bars are preferably of such length as to extend completely across the side on which they are mounted and around the adjacent corners in end portions 13. The other two inner faces of the casing 10 are provided with angle irons 14 and 15 secured thereto by bolts 16 which pass through the casing 10, the ends 13 of bars 11, and the angle irons 14 and 15.

A pair of suspension brackets 17 are mounted across the corners of the casing 10 adjacent the angle iron 15. These suspension brackets 17 are preferably made of relatively thick stock (for example, $\frac{1}{2}$ inch stock) and are apertured at one end for the reception of the mounting bolt 18 which secures the bracket to the angle iron 15. The brackets 17 are provided with a pair of tapped holes 19 in their opposite ends for receiving a pair of bolts 20 whose heads are countersunk in the bar 11 and do not extend through the wall of casing 10.

A supporting base or spider 21 is suspended directly from the angle iron 16 and the suspension bracket 17 by means of a plurality of suspension members 22 which will be described in greater detail hereinafter.

Substantially all of the principal operating and control mechanism of the washing, rinsing and drying machine is mounted on and carried by spider 21. It will be observed from Figure 1 that a tub 23 is mounted on the spider 21 and rotatably mounted within the tub is a perforated

drying basket 24. Within the drying basket 24 and mounted concentrically with respect to the mounting for drying basket 24 is an agitator 25 which is arranged to be oscillated during the washing operation. Suspended from the under side of spider 21 are driving means, transmissions, pump means and suitable clutch and control means which are described in greater detail in the aforementioned parent application Serial No. 368,190, but not shown here for the reason that they form no part of the present invention.

The details of construction of the suspension members 22 and their associated structure may best be seen from an inspection of Figures 2 and 3. The opposite ends of the suspension rod 26 of each suspension member 22 are drilled and tapped for the reception of the threaded shank of a bolt 27. The bolts 27 are provided with relatively large heads 28 about each of which is formed a molded rubber cushioning pad 29. A lock nut 30 is provided on each bolt 27 to limit the extent to which the bolt may be screwed into the suspension rod 26.

Each cushioning pad 29 is contained within a suspension pad socket 31. The lower suspension pad socket 31 is closed off by means of a bracket 32 which is centrally apertured to permit free movement of the suspension member 22 and the shank of its associated bolt 27 to freely move therein. The bracket 32 serves to prevent the rubber cushioning pad 29 from coming out of the socket 31. The bracket 32 is bolted to a pair of projecting ears 33 formed on spider 21 by means of bolts 34. The lower suspension pad socket 31 is bolted to brackets 32 by means of bolts 35 which extend from the base of the socket 31 alongside of the cushioning pad 29 (see Figure 3).

The upper suspension pad socket 31 for the suspension member 22 located at the right hand side of Figure 1 is closed by a cover plate 36 and is directly bolted to a slightly bent up portion 37 of the angle iron 14 by means of bolts 38 which extend from the base of the socket 31 through the cover plate 36 and the bent-up portion 37 of the angle iron 14. The remaining two suspension members 22 which are supported from the suspension bracket 17 are generally similar to the suspension member 22 connected to the angle iron 14 with the exception that the cover plate 36 of each of the former suspension rods and the socket 31 are directly bolted to the bracket 17.

From the above description, it will be understood that a substantially floating mounting is provided for spider 21 with respect to the substantially rigid casing 10. It will be noted that the portion of the rubber cushioning pad 29 above bolt head 28 in the lower socket 31 is under a compressive force, while the portion of the rubber cushioning pad 29 below the bolt head 28 in the upper socket member 31 is also subjected to a compressive force. By virtue of this arrangement, it will be understood that an essentially non-rigid supporting means is provided for spider 21 together with the control and operating mechanism mounted thereon with respect to casing 10.

The effectiveness of such a resilient mounting as is provided by the present invention is facilitated by an arrangement of the several parts of the operating and control mechanism suspended from the under side of spider 21 so as to provide a substantially equally distributed load at each of the three points of suspension in the structure illustrated in Figure 1. The same results may be obtained, however, by varying the number and disposition of the suspension members 22. Furthermore, by artificially loading the spider 21, i. e. by making it abnormally heavy, its inertia is increased, and thus tends to reduce vibration in the machine.

While we have shown and described particular embodiments of our invention, it will, of course, be understood that we do not wish to be limited thereto, since many modifications may be made, and we, therefore, contemplate, by the appended claim to cover all such modifications as fall within the true spirit and scope of our invention.

We claim as our invention:

In a laundry machine having a substantially rectangular casing, means for suspending the operating mechanism of said machine in said casing comprising a base member, angularly disposed plates secured to said frame members in two adjacent corners of said casing and a third plate substantially centrally disposed on the opposite side of said casing, and means including resilient support means connected between said plates and said base.

PETER EDUARD GELDHOF.
